UNITED STATES PATENT OFFICE.

LOUIS WOJIDKOW, OF BROOKLYN, NEW YORK.

DESIGN FOR A TEA-KETTLE.

SPECIFICATION forming part of Design No. 27,942, dated December 7, 1897.

Application filed October 20, 1897. Serial No. 655,860. Term of patent 3½ years.

To all whom it may concern:

Be it known that I, LOUIS WOJIDKOW, a citizen of the United States, residing at Brooklyn, county of Kings, and State of New York, 5 have invented and produced a new and original Design for Tea-Kettles, of which the following is a specification, reference being had to the accompanying drawings, forming part thereof.

- 10 Figure 1 is a side view of a teakettle, showing my new design; and Fig. 2 is a plan view of the same.

As shown in the drawings, the leading or material feature of my design consists of a 15 bulged body around the larger portion of which extends a beaded border.

- 20 A indicates the body of the kettle, which is bulged outwardly at *a*, while around this bulged portion extends a beaded border *B*.

The top part *C* of the body is formed on a

compound curve the rim of which is also furnished with a beaded border *D*, while above the beaded border *D* is a dome-shaped apex *E*.

F indicates the grip of the handle, which handle is provided with side bars *F'*, rising 25 from the top part *C* and having distinct outwardly-projecting angular portions *f* at their upper parts.

Having described my invention, what I claim as new, and desire to secure by Letters 30 Patent, is—

The design for a tea-kettle, substantially as herein shown and described.

In testimony that I claim the foregoing as my invention I have signed my name in presence of two subscribing witnesses,

LOUIS WOJIDKOW.

Witnesses:

GEO. W. JAEKEL,

PAUL GOEPEL.
